Patented April 18, 1905.

UNITED STATES PATENT OFFICE.

RUDOLPH VON HAGEN, OF WALLINGFORD, CONNECTICUT, ASSIGNOR TO
THE SIMEON L. AND GEORGE H. ROGERS CO., OF WALLINGFORD, CON-
NECTICUT, A FIRM.

DESIGN FOR A HANDLE FOR SPOONS, FORKS, OR SIMILAR ARTICLES.

SPECIFICATION forming part of Design No. 37,407, dated April 18, 1905.

Application filed March 25, 1905. Serial No. 252,082. Term of patent 7 years.

To all whom it may concern:

Be it known that I, RUDOLPH VON HAGEN, a citizen of the United States, residing at Wallingford, in the county of New Haven and State of Connecticut, have invented a new, original, and ornamental Design for a Handle for a Spoon, Fork, or Similar Article; and I do hereby declare the accompanying drawing to be a full, clear, and exact illustration of the same, and which said drawing constitutes

part of this specification and represents a face view of a handle for a spoon, fork, or similar article embodying my design.

I claim—

The ornamental design for a handle for a spoon, fork or similar article as shown.

RUDOLPH VON HAGEN.
